CASTING PRESS PLATES

Henry F. Hagemeyer, Chicago, Ill., assignor to
 Castings Patent Corporation, a corporation of
 Illinois

Application May 5, 1938, Serial No. 206,149

6 Claims. (Cl. 22—90)

My invention relates to casting presses, and more specifically to pressure plates used in conjunction with a press for holding together the cope and drag of a mold during the operation of pouring the molten metal into the mold.

In pouring a mold it is desirable to have the mold sections pressed together with sufficient force to prevent the molten metal from escaping between the parting surfaces under the pressure exerted by the metal as it flows into the mold cavity. To enable better regulation and quicker application of pressure to the mold sections I prefer to use a fluid pressure cylinder, as illustrated in my copending application Serial No. 207,932, filed May 14, 1938, for Casting mechanism, instead of weights or clamps. My invention, however, is adapted for use with any of these types of pressure means.

In preparing molds of the plastic or gypsum base type, it has been found that the mold material sets with more or less of a meniscus on its outer or exposed surface. When smooth, rigid, pressure plates have been used, therefore, it has been necessary to scrape or otherwise finish the back of each mold section to a plane surface in order to obtain uniform pressure over the entire area thereof, which is necessary to prevent unequal or warping stresses in the mold tending to crack it, and to prevent excessive localized pressure between small areas of the parting surfaces. Such smoothing of the mold section back takes considerable time which increases the expense of preparing the molds, and further is likely to result in breaking off corners or edges of the brittle dried mold.

I have found that the pressure of the pressing mechanism may be distributed substantially uniformly over the back of a mold having a slight concavity or meniscus by the use of a rigid plate having relatively sharp ridges or projections about its margin with ridges or projections of greater area on its central portion, or even with an unbroken central portion. It is preferable, however, to have grooves throughout the surface of the plate to permit escape of gas exuding through the mold, and I also prefer that all the projections be of the same height.

My principal object, therefore, is to provide a pressure plate to transmit pressure from pressure creating means substantially uniformly over the surface of a mold having a slightly concave contact surface or one having a meniscus.

Another object is to provide such a plate which will be adapted for use on different molds having contact surfaces with more or less concavity or meniscus.

A further object is to provide a pressure transmitting plate which will not interfere with and may expedite the escape from the mold back of gas exuding through the mold body from the cavity.

It is also desired to make such mechanism compact and durable, although economical to construct and efficient in use.

Other objects will be made clear in the following detailed description of the preferred embodiment of my invention which is shown in the accompanying drawing to illustrate the principles and operation of such invention. The novel features thereof are defined in the appended claims.

Fig. 1 is a plan view showing one half of the preferred form of my pressure plate, which is symmetrical about the center line shown, and

Fig. 1A is a plan view showing one half of a modified form of such plate, also symmetrical about its indicated center line.

Fig. 2 is an end elevation of either the plate of Fig. 1 or that of Fig. 1A.

Fig. 3 is a side elevation of the half plate of Fig. 1, and

Fig. 3A is a side elevation of the half plate of Fig. 1A.

Fig. 4 is a side elevation of the pressure plate and mold assembly, illustrating the use of plates such as shown in Figs. 1A and 3A.

Fig. 5 is a fragmentary perspective view of a portion of the plate illustrated in Figs. 1 and 3, and

Fig. 6 is a fragmentary end elevation with parts in section, showing the engagement of a pressure plate with a mold face.

As has been mentioned, the projections or ribs on the pressure plates serve two purposes, first that of providing intermediate grooves to convey to the edge of the mold and plate assembly gases exuding from the mold cavity through the body thereof and escaping from the mold back, and second, to distribute the pressure substantially uniformly over the mold sections and to avoid appreciable unequal stressing thereof when the mold back has a slight concavity or meniscus. To accomplish the first purpose it is not necessary that the projections be of non-uniform area, but to equalize the pressure distribution over the concave mold back the marginal projections should be of smaller area than the central ones, to penetrate into the fillets a distance sufficient to enable the central projections to engage the mold back firmly. As far as the second purpose

is concerned, it will be appreciated that the central portion might be unbroken by grooves.

A pressure plate designed for a nearly square mold should be like that indicated as 1 in Figs. 1 and 3, having two sets of grooves 10 and 11 which mutually intersect. The plate is preferably rectangular in shape and one set of grooves consists of parallel grooves which most conveniently are also arranged parallel to the longitudinal edges 10 of the plate. Likewise, the cross grooves 11 are preferably parallel to each other and parallel also to the ends of the plate 1, so that the grooves of the two sets intersect at right angles.

In the central portion of the plate may be 15 projections in the form of ribs 12 which are defined by the respective grooves 10. It will be noted that these grooves extend beyond the edge of the mold M resting thereon, as shown in Fig. 4, to be in free communication with the atmosphere 20 when the plate is in pressing engagement with the mold. Preferably, these grooves extend clear to the edge of the plate 1 to form notches therein as shown in Fig. 2. The gases escaping from the mold back will thus have a positive passage for 25 their exit from between the mold and the pressure plate. For still better ventilation, the grooves 11 may also extend clear to the edge of the plate 1 to form notches therein as shown in Fig. 3. Such provision is desirable where the 30 meniscus is pronounced. As shown in Fig. 6, the meniscus tends to clog the grooves partially and the increase in the exit opening effected by the cross grooves compensates for such clogging. If desired, the grooves may be made progressively 35 wider toward the edge of the plate to increase the vent still further.

To obtain substantial uniformity of pressure over a mold surface having a meniscus, the surface of a rigid pressure plate might be made complementary convex. Such an expedient is not 40 entirely satisfactory, however, for the same plate must be used on mold surfaces of widely varying degrees of concavity, and such a rigid plate could be made accurately complementary to a mold of 45 only one degree and shape of concavity. Moreover, the machining of a plate surface substantially plane in the center and having a margin with a convexity progressively varying in degree is a difficult task. I have therefore made the 50 projections, including the ribs or ridges 12 and the buttons 13 all of the same height, but have spaced the grooves nearer together at the margins than in the central portion of the plate. The central projections defined by such grooves are 55 consequently of greater width and area than those at the margins. As such a plate is forced against the face of a mold the small marginal projections will be compelled to penetrate into the meniscus, as indicated in Fig. 6, until the 60 central portion of the plate seats on the plane central portion of the mold back.

Over the central portion of the plate the ribs or projections should be of substantially the same area, and toward the margins of the surface they 65 may be progressively narrower, or several rows of narrow projections of equal width may be provided along the margins. When such narrow marginal projections are employed, however, I prefer to interpose between them and the relatively wide central projections several rows of 70 projections of intermediate width, as illustrated in the drawing.

With any such arrangement the spacing between any two successive marginal grooves will 75 be at least as great as the spacing between any

two successive grooves nearer the center of the plate. Likewise, the width of every projection or rib will be at least as great as that of every projection or rib disposed closer than itself to the edge of the plate. Because more gas will ordinarily be liberated from the central portion of the mold surface, I prefer that the width of the central grooves be greater than that of the marginal grooves.

Obviously, the number and widths of the projections, the number, widths and depths of the grooves, and the relative widths and depths of the marginal and central grooves and projections, as well as of the two sets of grooves and projections, may be varied considerably according to the 15 average requirements of a particular installation. Precautions should be taken, however, to make the marginal projections sufficiently narrow so that the meniscus will be penetrated deeply enough to enable the central portion or projections of the plate to come into firm pressing engagement with the mold without the marginal portions of the mold being subjected to excessive pressure. In order to allow the marginal projections to penetrate thus but still to exert finally 20 substantially their proportionate share of the pressure on the mold, I prefer that at least the marginal projections be tapered from their bases to their ridges, so that as the penetration of each projection increases the pressure exerting area 25 thereof also becomes progressively greater.

If the mold, instead of being nearly square, is 30 relatively long and narrow, the meniscus along the ends of the plate may be negligible. For such cases the cross grooves 11 may be omitted and the ribs 12 may extend uninterruptedly from end to end of the plate, as shown in Figs. 1A, 3A and 4. The notched formation of Fig. 2 will press into and perhaps serrate the slight meniscus at each end sufficiently to enable the central portions of the ribs to come into contiguous engagement with the mold back. The narrow ribs along the longer edges of the plate will, of course, penetrate into the meniscus along each such edge as has been described and as shown in Fig. 6.

While, for purposes of illustration, the construction of the lower pressure plate has been 45 shown in detail, the upper pressure plate 2, pictured in Fig. 4, will be provided with projections and grooves in the same manner as plate 1. An escape for pouring gases and substantial uniformity of pressure will therefore be provided for both upper and lower mold surfaces.

Escape of the air and pouring gases from the mold cavity through the mold body may, if desired, be expedited by sealing the edges of the pressure plates and the groove ends, and then evacuating the grooves through the body of each plate to increase the pressure differential between the mold cavity and mold back. Such lowered pressure would also induce flow of air into the edges of the porous mold and out the mold back, tending to cool the metal in the mold cavity, such cooling being greatest in the marginal portions of the mold and progressively decreasing toward 55 the center, so that solidification, and cooling, and hence shrinkage, would occur in the order of first the castings from their outer portions inward, then the gates, then the runners and finally the sprue.

As my invention, I claim:

1. A mold engaging pressure plate having on one face thereof mold engaging projections defined by intersecting sets of generally parallel grooves, the spacing between adjacent edges of successive 75

grooves of each set in the central portion of the plate being greater than the spacing between adjacent edges of successive grooves of the same set near the margin of the plate.

3. 2. A rectangular mold engaging pressure plate having on one face thereof mold engaging projections defined by a set of parallel grooves disposed parallel to opposite edges of the plate and a second set of parallel grooves disposed perpendicular to said first set of grooves and parallel to the other opposite edges of the plate, the spacing between adjacent edges of successive grooves of each set in the central portion of the plate being greater than the spacing between adjacent edges 10 of successive grooves of each set, respectively, disposed near the edge of the plate.

3. A mold engaging pressure plate having on one face thereof coplanar mold engaging projections adapted to be in simultaneous engagement 20 with a mold back, and defined by a plurality of successive grooves, the spacing between adjacent edges of successive grooves in the central portion of the plate being greater than the spacing between adjacent edges of successive grooves near 25 the edge of the plate.

4. A rectangular mold engaging pressure plate having on one face a plurality of parallel ribs disposed parallel to opposite plate edges, each rib being at least as wide as every rib disposed closer

to the plate edge than such rib, and the centrally disposed ribs being wider than the ribs adjacent to the plate edge, and the space between adjacent edges of adjacent centrally disposed ribs being greater than the space between adjacent edges of 5 adjacent ribs near the plate edge.

5. A mold engaging pressure plate having on its mold engaging face a plurality of mold engaging buttons of small mold engaging surface area spaced along the plate edges, and in the central 10 portion of such face a mold engaging projection of relatively large mold engaging surface area as compared to that of such a button along the plate edge.

6. A mold engaging pressure plate, having a 15 planar mold engaging surface including a central contact zone and a marginal contact zone adapted to be in simultaneous engagement with a mold back, both zones of contact being interrupted by depressions defining a plurality of narrow mold engaging surface portions in the marginal zone, adapted to penetrate a marginal meniscus on a mold back, and a plurality of relatively wide mold engaging surface portions in the central zone, adapted to abut the central 20 25 portion of a mold back, thereby to distribute substantially uniformly over the mold back the pressure exerted thereon by the pressure plate.
